ROTARY FOR DRILLING WELLS

John D. Bennett, Beaumont, Tex., assignor to
 International Derrick & Equipment Company,
 Columbus, Ohio, a corporation of Ohio

Application February 17, 1947, Serial No. 729,154

11 Claims. (Cl. 255—23)

1

The invention concerns a rotary having a rotary table which is rotatably supported in a base and is driven by a horizontally disposed drive shaft having a pinion gear on one end thereof adapted to engage a ring gear secured to the rotary table.

The invention concerns more particularly a novel arrangement for supporting the rotary table in the base and for accomplishing other purposes which will be more fully described.

It is an object of the invention to provide an arrangement in which the bearings supporting the rotary table are positioned in substantially the same horizontal plane as the teeth of the ring gear and the uppermost teeth of the pinion gear. This arrangement is desirable in order to avoid any tendency of the force exerted by the pinion gear to tilt the table. Such a tendency normally exists in arrangements in which the bearings supporting the table are positioned at a lower elevation than the driving gears, the horizontal thrust exerted by the pinion gear tending to throw the upper part of the table horizontally while the lower part of the table remains in fixed position. The condition described causes undue wear of the parts which act to retain the table in the base.

It is also an object of the invention to provide an arrangement in which the bearings supporting the rotary table are positioned in the upper part of the rotary and are protected against mud and water which may be thrown upwardly into the rotary from the well being drilled.

It is a further object of the invention to provide an arrangement in which the bearings supporting the rotary table are positioned above and supported by a retaining ring which is removably secured to the base and is adapted to retain the table in the base, the arrangement being such that the table, the bearings and the retaining ring may be assembled as a unit and the entire assembly may be inserted in and withdrawn from the base at one time.

Other advantageous features of the invention will be apparent from the following description and the accompanying drawing.

Fig. 1 is a top view of a rotary embodying the invention.

Fig. 2 is a longitudinal view in elevation. In the lower left hand portion of the drawing a part of the apparatus is shown as viewed from the exterior, the remainder of the drawing being a sectional view taken on line 2—2 of Fig. 1.

Fig. 3 is an enlarged plan view of a portion of the apparatus shown in Fig. 2.

2

Referring to the drawing, a base is provided, the base being shaped generally like a rectangular box and having a pair of side walls 1, a pair of end walls 2, a top wall 3 and a bottom wall 4. One end of the base is open at the bottom, while of end walls 2, a top wall 3 and a bottom wall 4. The base is supported on a pair of runners 5 which are joined at one end by a turned up portion 6 and are adapted to serve as a skid. The turned up portion 6 extends outwardly from the end wall 2 and is joined thereto by a lug 7 which is provided with an opening 8 adapted to be engaged by a towing or lifting device. U. S. Patent No. 2,276,561, dated March 17, 1942, and issued to Richard R. Bloss, describes and claims an arrangement which includes these features.

A circular well is formed in the base adapted to receive a rotary table. The well is of smaller diameter at the bottom than at the top and is formed by an annular wall 9 which extends upwardly from the bottom of the base, an annular wall 10 which extends downwardly from the top of the base, and a connecting ring 11 which connects the annular walls 9 and 10. The connecting ring 11 is depressed adjacent the periphery of the upwardly extending wall 9 and extends outwardly and upwardly from a point near the top thereof to form an annular gutter 12. The walls 9 and 10 and the ring 11 are formed integrally with the side walls 1, the top wall 3 and the bottom wall 4, and are supported on the runners 5 by ribs 13 which extend inwardly from the side walls 1 and which also support the side walls 1 and the bottom wall 4.

35 A rotary table is provided which has a circular top 14 and a depending annular wall 15, the depending wall 15 being of smaller diameter than the top 14. The lower end of the depending wall 15 is receivable in the upwardly extending wall 9. A ring 16 extends outwardly from the depending wall 15, and an annular groove 17 is formed in the depending wall 15 adjacent the outwardly extending ring 16 adapted to receive the top of the upwardly extending wall 9. A retaining ring 18 extends inwardly from the connecting ring 11, above the annular gutter 12, and is adapted to slidably engage the outwardly extending ring 16 to retain the rotary table in the base. The retaining ring 18 is removably secured to the connecting ring 11 by a series of bolts 19. The walls of the connecting ring 11 are thickened adjacent the bolts 19. The upper ends of the bolts 19 are screwed into the retaining ring 18 and are permanently secured thereto by brazing applied to the ends thereof within depressions 20

which are formed in the upper side of the retaining ring 18.

The retaining ring 18 is formed in two halves which are fastened together by bolts after they are placed in position about the depending wall 15 above the outwardly extending ring 16. An outer race ring 21 is secured to the upper side of the retaining ring 18 and an inner race ring 22 is secured to the under side of the table top 14. Ball bearings 23, having a spacing ring 24, are positioned between the race rings 21 and 22 and are adapted to rotatably support the rotary table. The arrangement is such that the rotary table, the bearings and the retaining ring 18 may be assembled as a unit and the entire assembly may be inserted in and withdrawn from the base at one time.

A ring gear 25 is secured to the under side of the table top 14 adjacent its periphery. A horizontally disposed drive shaft 26 is rotatably mounted in the base, as hereinafter described. A pinion gear 27 is secured to one end of the drive shaft 26 and is rotatable therewith. The pinion gear 27 projects thru an opening in the downwardly extending annular wall 10 and the connecting ring 11 and is adapted to engage the ring gear 25 to rotate the rotary table.

The drive shaft 26 extends thru the center of and is rotatably mounted in a horizontally disposed cylindrical housing 28, the drive shaft 26 and the housing 28 being assembled as a unit and inserted thru an opening 29 in an end wall 2. The housing 28 is provided at its ends with shoulders 30 adapted to support the housing 28 in the opening 29 and an opening 31 formed in an inner wall 32. A flange 33 is formed on the outer end of the housing 28 and is secured to the end wall 2 by a series of bolts 34. The inner end of the drive shaft 26 is rotatably supported in the housing 28 by roller bearings 35 which have inner and outer race rings 36 and 37. A retaining ring 38, which is secured to the inner end of the housing 28 by a series of bolts 39, acts to retain the bearings 35 in the housing 28. The outer end of the drive shaft 26 is rotatably supported in the housing 28 by roller bearings 40 which have inner and outer race rings 41 and 42. An oil seal 43 is provided at the outer end of the bearings 40, and a retaining ring 44, which is secured to the outer end of the housing 28 by a series of bolts 45, acts to retain the bearings 40 in the housing 28.

A sprocket 46 is keyed on the tapered outer end of the drive shaft 26 and is secured thereto by a retaining nut 47 which is screwed on the end of the drive shaft 26 and additionally secured thereto by a cap-screw 48 to prevent the retaining nut 47 from unscrewing due to vibration.

The rotary table is lubricated by an oil bath system, the base being filled with oil to a level sufficient to immerse at least the lowermost teeth of the pinion gear 27. An oil reservoir 49 is formed in the base adjacent the pinion gear 27, and a discharge opening 50 is provided in the bottom wall 4 at that point for draining. Oil is circulated thru the interior of the housing 28 to lubricate the bearings 35 and 40. An oil collecting gutter 51 formed about the upper surface of the retaining ring 38 communicates with a channel (not shown) leading to the interior of the housing 28. Discharge openings 52 and 53 are provided in the bottom of the housing 28 and the bottom wall 4 for draining the interior of the housing 28 and the portion of the base which surrounds it. The annular gutter 12 is provided with a discharge opening 54 which communicates with the

oil reservoir 49. In operation the pinion gear 27 picks up oil from the oil reservoir 49 and carries it upwardly to the ring gear 25, from which oil is splashed over the ball bearings 23 and the oil collecting gutter 51. Oil draining from the ball bearings 23 is collected in the annular gutter 12 and returned to the reservoir 49 thru the discharge opening 54.

A locking ring 55 is secured about the periphery of the table top 14. Slots 56 are formed in the periphery of the locking ring 55 adapted to receive a locking pin 57. The locking pin 57 is retained in a slot 58 formed in the base, and is adapted to be moved longitudinally in and out of locking engagement with the slots 56. A lever 59 is secured to the outer end of the locking pin 57 and is receivable in either of two slots 60, which extend transversely with respect to the slot 58, to secure the locking pin 57 in operative and inoperative positions, respectively. This arrangement is described and claimed in a patent application of Richard R. Bloss, Serial No. 751,673.

An annular groove 61 is formed in the under side of the locking ring 55 adapted to receive the top of the annular wall 10. A seal ring 62, which projects inwardly from the top of the annular wall 10, is adapted to slidably engage a groove 63 formed in the periphery of the table top 14 below the locking ring 55. A baffle ring 64 projects inwardly from the annular wall 10 and is adapted to knock back any lubricating oil that may be splashed upwardly against it. U. S. Patent No. 2,276,561, dated March 17, 1942, and issued to Richard R. Bloss, describes and claims an arrangement which includes these features. A guard ring 65 is secured to the top wall 3 about the table top 14, above the locking ring 55.

The working parts of the rotary are entirely enclosed and are protected against mud and water which may come in contact with the rotary. The arrangement is such that most of the mud and water that falls on top of the rotary will run off the sides. The space between the table top 14 and the guard ring 65 is small, and the arrangement is such that mud and water which may pass downwardly thru such space will not come in contact with the driving gears or the bearings. Likewise mud and water which may be thrown upwardly into the rotary from the well being drilled, and which may enter the space between the upwardly extending annular wall 9 and the depending wall 15, will collect in the annular gutter 12 and be discharged therefrom without coming in contact with the driving gears or the bearings.

The rotary table is provided with a central opening adapted to receive either a Kelly drive or a pair of slips. The drawing shows a Kelly drive 66, which is formed in two halves fastened together by bolts 67. The upper part of the central opening, indicated by the numeral 68, is generally circular in shape and a series of radially spaced slots 69 are formed in the wall surrounding the opening adapted to engage corresponding lugs 70 which are formed about the periphery of the Kelly drive 66. The wall surrounding a middle portion of the central opening, indicated by the numeral 71, is tapered and is adapted to receive a pair of slips. The wall surrounding the extreme lower part of the central opening, indicated by the numeral 72, is adapted to engage a shoulder 73 formed on the lower end of the Kelly drive 66. The exterior surface of the Kelly drive 66 does not engage the wall surround-

ing the middle portion of the central opening, indicated at 72, the tapered surface at this point being reserved for engagement by the slips. This arrangement is described and claimed in a patent application of Richard R. Bloss, Serial No. 751,673.

The invention as described herein may be modified in various ways without departing from the spirit and scope thereof.

I claim:

1. A rotary for drilling wells comprising a base having an upwardly extending annular wall, a rotary table having a circular top and a depending annular wall of smaller diameter than the top, the lower end of the depending wall being receivable in the upwardly extending wall, a ring extending outwardly from the depending wall, a ring extending outwardly and upwardly from a point near the top of the upwardly extending wall, a retaining ring removably secured to and extending inwardly from the last mentioned ring adapted to slidably engage the outwardly extending ring to retain the rotary table in the base, bearings positioned above and supported by the retaining ring adapted to rotatably support the rotary table, and a ring gear secured to the under side of the table top adjacent its periphery, the bearings supporting the rotary table being positioned in substantially the same horizontal plane as the teeth of the ring gear.

2. A rotary for drilling wells comprising a base having a circular well adapted to receive a rotary table, the well being of smaller diameter at the bottom than at the top and being formed by an annular wall extending upwardly from the bottom of the base, an annular wall extending downwardly from the top of the base and a connecting ring connecting the annular walls, the connecting ring being depressed adjacent the periphery of the upwardly extending wall and extending outwardly and upwardly from a point near the top of the upwardly extending wall to form an annular gutter, a rotary table having a circular top and a depending annular wall of smaller diameter than the top, the lower end of the depending wall being receivable in the upwardly extending wall, a ring extending outwardly from the depending wall, an annular groove in the depending wall adjacent the outwardly extending ring adapted to receive the top of the upwardly extending wall, a retaining ring removably secured to the connecting ring and extending inwardly therefrom, above the annular gutter, adapted to slidably engage the outwardly extending ring to retain the rotary table in the base, and bearings positioned above and supported by the retaining ring adapted to rotatably support the rotary table.

3. A rotary for drilling wells comprising a base having a circular well adapted to receive a rotary table, the well being of smaller diameter at the bottom than at the top and being formed by an annular wall extending upwardly from the bottom of the base, an annular wall extending downwardly from the top of the base and a connecting ring connecting the annular walls, the connecting ring being depressed adjacent the periphery of the upwardly extending wall and extending outwardly and upwardly from a point near the top of the upwardly extending wall to form an annular gutter, a rotary table having a circular top and a depending annular wall of smaller diameter than the top, the lower end of the depending wall being receivable in the upwardly extending wall, a ring extending outwardly

from the depending wall, an annular groove in the depending wall adjacent the outwardly extending ring adapted to receive the top of the upwardly extending wall, a retaining ring removably secured to the connecting ring and extending inwardly therefrom, above the annular gutter, adapted to slidably engage the outwardly extending ring to retain the rotary table in the base, bearings positioned above and supported by the retaining ring adapted to rotatably support the rotary table, a ring gear secured to the under side of the table top adjacent its periphery, a horizontally disposed drive shaft rotatably mounted in the base and projecting thru an opening formed in the upper part of the well, and a pinion gear secured to one end of the drive shaft and rotatable therewith, the pinion gear being adapted to engage the ring gear to rotate the rotary table.

4. A rotary for drilling wells comprising a base having a circular well adapted to receive a rotary table, the well being of smaller diameter at the bottom than at the top and being formed by an annular wall extending upwardly from the bottom of the base, an annular wall extending downwardly from the top of the base and an outwardly and upwardly extending connecting ring connecting the annular walls, a rotary table having a circular top and a depending annular wall of smaller diameter than the top, the lower end of the depending wall being receivable in the upwardly extending wall, a ring extending outwardly from the depending wall, a retaining ring removably secured to the connecting ring and extending inwardly therefrom adapted to slidably engage the outwardly extending ring to retain the rotary table in the base, bearings positioned above and supported by the retaining ring adapted to rotatably support the rotary table, and a ring gear secured to the under side of the table top adjacent its periphery, the center line of the bearings being in a horizontal plane which is not lower than the lowermost extremity of the teeth of the ring gear.

5. A rotary for drilling wells comprising a base having a circular well adapted to receive a rotary table, the well being of smaller diameter at the bottom than at the top and being formed by an annular wall extending upwardly from the bottom of the base, an annular wall extending downwardly from the top of the base and an outwardly and upwardly extending connecting ring connecting the annular walls, the upwardly extending wall extending upwardly to a point not lower than the center line of the rotary, a rotary table having a circular top and a depending annular wall of smaller diameter than the top, the lower end of the depending wall being receivable in the upwardly extending wall and extending downwardly to the lower end thereof, the interior surface of the upwardly extending wall and the exterior surface of the depending wall being cylindrical and concentric and the space between them being restricted, a ring extending outwardly from the depending wall, a retaining ring removably secured to the connecting ring and extending inwardly therefrom adapted to slidably engage the outwardly extending ring to retain the rotary table in the base, bearings positioned above and supported by the retaining ring adapted to rotatably support the rotary table, and a ring gear secured to the under side of the table top adjacent its periphery, the center line of the bearings being in a horizontal plane which is not lower than the lowermost extremity of the teeth of the ring gear and the arrangement being such that mud and water is prevented from reaching the

bearings by the elevated position of the bearings in the base of the rotary and the limited clearance between the upwardly extending wall and the depending wall.

6. A rotary for drilling wells comprising a base having a circular well adapted to receive a rotary table, the well being of smaller diameter at the bottom than at the top and being formed by an annular wall extending upwardly from the bottom of the base, an annular wall extending downwardly from the top of the base and a connecting ring connecting the annular walls, the connecting ring being depressed adjacent the periphery of the upwardly extending wall and extending outwardly and upwardly from a point near the top of the upwardly extending wall to form an annular gutter, a rotary table having a circular top and a depending annular wall of smaller diameter than the top, the lower end of the depending wall being receivable in the upwardly extending wall, a ring extending outwardly from the depending wall, a retaining ring removably secured to the connecting ring and extending inwardly therefrom, above the annular gutter, adapted to slidably engage the outwardly extending ring to retain the rotary table in the base, bearings positioned above and supported by the retaining ring adapted to rotatably support the rotary table, and a ring gear secured to the under side of the table top adjacent its periphery, the center line of the bearings being in a horizontal plane which is not lower than the lowermost extremity of the teeth of the ring gear.

7. A rotary for drilling wells comprising a base having a circular well adapted to receive a rotary table, the well being of smaller diameter at the bottom than at the top and being formed by an annular wall extending upwardly from the bottom of the base, an annular wall extending downwardly from the top of the base and an outwardly and upwardly extending connecting ring connecting the annular walls, a rotary table having a circular top and a depending annular wall of smaller diameter than the top, the lower end of the depending wall being receivable in the upwardly extending wall, a ring extending outwardly from the depending wall, an annular groove in the depending wall adjacent the outwardly extending ring adapted to receive the top of the upwardly extending wall, a retaining ring removably secured to the connecting ring and extending inwardly therefrom adapted to slidably engage the outwardly extending ring to retain the rotary table in the base, bearings positioned above and supported by the retaining ring adapted to rotatably support the rotary table, and a ring gear secured to the under side of the table top adjacent its periphery, the center line of the bearings being in a horizontal plane which is not lower than the lowermost extremity of the teeth of the ring gear.

8. A rotary for drilling wells comprising a base having a circular well adapted to receive a rotary table, the well being of smaller diameter at the bottom than at the top and being formed by an annular wall extending upwardly from the bottom of the base, an annular wall extending downwardly from the top of the base and a connecting ring connecting the annular walls, the connecting ring being depressed adjacent the periphery of the upwardly extending wall and extending outwardly and upwardly from a point near the top of the upwardly extending wall to form an annular gutter, a rotary table having a

circular top and a depending annular wall of smaller diameter than the top, the lower end of the depending wall being receivable in the upwardly extending wall, a ring extending outwardly from the depending wall, an annular groove in the depending wall adjacent the outwardly extending ring adapted to receive the top of the upwardly extending wall, a retaining ring removably secured to the connecting ring and extending inwardly therefrom, above the annular gutter, adapted to slidably engage the outwardly extending ring to retain the rotary table in the base, bearings positioned above and supported by the retaining ring adapted to rotatably support the rotary table, a ring gear secured to the under side of the table top adjacent its periphery, the center line of the bearings being in a horizontal plane which is not lower than the lowermost extremity of the teeth of the ring gear, a discharge opening being formed in the annular gutter and the arrangement being such that mud and water which may enter the space between the upwardly extending wall and the depending wall will collect in the annular gutter and be discharged therefrom without coming in contact with the gears or the bearings.

9. A rotary for drilling wells comprising a base having a circular well adapted to receive a rotary table, the well being of smaller diameter at the bottom than at the top and being formed by an annular wall extending upwardly from the bottom of the base, an annular wall extending downwardly from the top of the base and an outwardly and upwardly extending connecting ring connecting the annular walls, a rotary table having a circular top and a depending annular wall of smaller diameter than the top, the lower end of the depending wall being receivable in the upwardly extending wall, a ring extending outwardly from the depending wall, a retaining ring removably secured to the connecting ring and extending inwardly therefrom adapted to slidably engage the outwardly extending ring to retain the rotary table in the base, bearings positioned above and supported by the retaining ring adapted to rotatably support the rotary table, a ring gear secured to the under side of the table top adjacent its periphery, a horizontally disposed drive shaft rotatably mounted in the base and a pinion gear secured to one end of the drive shaft and rotatable therewith, the pinion gear being adapted to engage the ring gear to rotate the rotary table, the center line of the bearings being in a horizontal plane which is not lower than the lowermost extremity of the teeth of the ring gear.

10. A rotary for drilling wells comprising a base having a circular well adapted to receive a rotary table, the well being of smaller diameter at the bottom than at the top and being formed by an annular wall extending upwardly from the bottom of the base, an annular wall extending downwardly from the top of the base and an outwardly and upwardly extending connecting ring connecting the annular walls, a rotary table having a circular top and a depending wall of smaller diameter than the top, the lower end of the depending wall being receivable in the upwardly extending wall, a ring extending outwardly from the depending wall, a retaining ring removably secured to the connecting ring and extending inwardly therefrom adapted to slidably engage the outwardly extending ring to retain the rotary table in the base, bearings positioned above and supported by the retaining ring

adapted to rotatably support the rotary table, a ring gear secured to the under side of the table top adjacent its periphery, a horizontally disposed drive shaft rotatably mounted in the base and a pinion gear secured to one end of the drive shaft and rotatable therewith, the pinion gear being adapted to engage the ring gear to rotate the rotary table, the center line of the bearings being in a horizontal plane which is not lower than the lowermost extremity of the teeth of the ring gear, the base having a bottom and side walls forming, with the upwardly extending wall of the well, an oil reservoir partially enclosing the pinion gear and the arrangement being such that in operation the pinion gear picks up oil from the oil reservoir and carries it upwardly to the ring gear, a part of the oil being splashed over the bearings.

11. A rotary for drilling wells comprising a base having a circular well adapted to receive a rotary table, the well being of smaller diameter at the bottom than at the top and being formed by an annular wall extending upwardly from the bottom of the base, an annular wall extending downwardly from the top of the base and a connecting ring connecting the annular walls, the connecting ring being depressed adjacent the periphery of the upwardly extending wall and extending outwardly and upwardly from a point near the top of the upwardly extending wall to form an annular gutter, a rotary table having a circular top and a depending annular wall of smaller diameter than the top, the lower end of the depending wall being receivable in the upwardly extending wall, a ring extending outwardly from the depending wall, a retaining ring removably secured to the connecting ring and extending inwardly therefrom, above the annular gutter, adapted to slidably engage the outwardly extending ring to retain the rotary table in the base, bearings positioned above and supported by the retaining ring adapted to rotatably support

the rotary table, a ring gear secured to the under side of the table top adjacent its periphery, a horizontally disposed drive shaft rotatably mounted in the base and a pinion gear secured to one end of the drive shaft and rotatable therewith, the pinion gear being adapted to engage the ring gear to rotate the rotary table, the center line of the bearings being in a horizontal plane which is not lower than the lowermost extremity of the teeth of the ring gear, the base having a bottom and side walls forming, with the upwardly extending wall of the well, an oil reservoir partially enclosing the pinion gear and a discharge opening being formed in the annular gutter, the discharge opening communicating with the oil reservoir, the arrangement being such that in operation the pinion gear picks up oil from the oil reservoir and carries it upwardly to the ring gear, a part of the oil being splashed over the bearings and at least a part of the oil draining from the bearings being collected in the annular gutter and returned to the oil reservoir thru the discharge opening.
